CLAIM

The ornamental design for a hybrid effects projector, scanner and laser simulator lighting device with adjustable mounting bracket, as shown and described.

DESCRIPTION

FIG. 1 is a rear perspective view of a hybrid effects projector, scanner and laser simulator lighting device with adjustable mounting bracket;

FIG. 2 is a front perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken line showing of the hybrid effects projector, scanner and laser simulator lighting device with adjustable mounting bracket is for the purpose of illustrating environmental structure and forms no part of the claimed design.
